DEVICE FOR FOLDING AND INITIALLY HOT-PRESSING MARGINAL EDGES OF SLITS IN FABRICS

Jack Snarck, Bronx, N. Y., assignor of one-fourth to Charles Harrison, Brooklyn, N. Y., and one-half to Joseph F. O'Brien, Englewood, N. J.

Application March 5, 1932, Serial No. 597,085

3 Claims. (Cl. 223—15)

This invention relates to improvements in device for folding and initially hot-pressing marginal edges of slits in fabrics.

Objects of this invention are to produce a device or tool for use in folding of the opposite edges of slits in fabrics, and particularly for folding the marginal edges of slits arranged between parallel rows of stitching in fagoting embroidery.

Another object of this invention is to produce a device which will, simultaneously with the folding of the marginal edges of such slits, provide for the application of heat or the hot-pressing of such marginal edges for the purpose of causing the same to be retained in turned or folded position.

Another object of this invention is to produce a device which in one operation accomplishes the functions of opening up the slit between parallel rows thereof in a fabric, turning and folding down the marginal edge or edges of such fabric, and ironing or hot-pressing the same to cause the folded edges to be retained in folded position.

With these and other objects in view, the invention comprises the combination of members and arrangement of parts so combined as to contact and co-operate with each other in the performance of the functions and the accomplishment of the results herein contemplated, and comprises in one of its adaptions the species or preferred form illustrated in the accompanying drawing, in which:—

Fig. 1 is a view in plan of a piece of material or fabric used in fagoting embroidery and superimposed upon a piece of vanishing fabric having a design stitched thereunto with a fagoting stitch and showing the fabric slit and the tool in the act of turning the edges;

Fig. 1^a is a section on the line 1^a—1^a of Fig. 1;

Fig. 2 is a side elevation of the device or tool;

Fig. 3 is a bottom view of the tool shown in Figs. 1 and 2.

Referring now to the drawing which illustrates a preferred embodiment of my invention, 1 indicates a piece of fabric or material to be embroidered, which I shall hereinafter call "an embroidery fabric", 2 indicates a piece of heat-dischargeable fabric, adapted on subjection to heat to be discharged and to be brushed away, and which, in the preferred embodiment of my invention, I utilize as a protective foundation fabric or protective element. As illustrated, the embroidery fabric is superposed over the heat-dischargeable fabric with the front face of the embroidery fabric abutting the dischargeable fabric, and a fagoting-embroidery stitch is stitched

through both of said fabrics. My preferred stitch, 3 comprises a chain-stitch portion 3', fagotting cross-threads 3a and connecting stitch portion 3b. When this stitch is made in the superposed embroidery fabric and dischargeable fabric, the cross-threads 3a extend beneath or on underside or bottom of the dischargeable fabric 2 and these fagotting embroidery threads will thus, as hereinafter described, be protected by this dischargeable fabric, which is stiff and tough, during the further operations on the fabric.

The stitch 3 being made through the embroidery fabric and the protecting heat-dischargeable element 2, the portion of embroidery fabric extending over the cross-threads and between the parallel edge-stitch portions 3' and 3b may be slit, as shown at 4 in Fig. 1 by a pair of scissors, a knife or in any other suitable manner, and in this slitting operation, the heat-dischargeable protective element 2, being disposed between the fabric 1 and the cross-threads 3a will serve as a protective foundation to prevent engagement and severing of cross-threads by the severing tool, thus permitting greater speed in manufacturing than would otherwise be possible.

After the fabric is slit as shown at 4 in Fig. 1, I open up the slit, turn over the edge and initially iron or hot-press the same, and for this purpose, I utilize a novel device combining in one tool a slit-opener, edge turner and initial hot-presser.

The slit-opening portion of this tool is inserted in the slit and upon sliding the tool along through the slit on the dischargeable fabric I turn or fold outwardly and downwardly in opposite directions the marginal edges adjacent to the slit and in the same operation I iron or hot-press these edges so as to cause such edges to initially retain their folded position.

As illustrated in Figs. 1, 2 and 3, inclusive, I utilize a tool having a pointed and upwardly inclined portion which is preferably semi-conic in configuration and is adapted for ready insertion in the slit to cause a raising of the fabric edges and this pointed semi-conic or upwardly-inclined portion merges with another portion for turning down such edges, and said tool also provides means for the initial pressing or ironing of such edges so as to cause them to maintain their folded condition.

As illustrated, my novel tool 5 includes a metallic body 6, having a neck portion 6a of predetermined or given width equal to the width of the fagotting slits the edges of which are to be folded and also having a pointed insertion head portion 7 provided with an upwardly-in-

clined edge-raising surface $7'$ merging with a reversely-inclined wall portion $7a$. Said wall portion $7a$ has a bevelled edge or conical surface $7b$ serving as an edge turning or guiding portion 5 and extending upwardly and outwardly from said neck portion and connected with pressing wing portions, as hereinabove specified. This bevel-edged or conical surface $7b$ of the wall $7a$ preferably surrounds the semiconic pointed nose, 10 constituting a major circumference merging at its lower ends with flat pressing wing portions beneath which the fabric margin is led to permit hot pressing, said pressing-wing portion of $7d$ merging with the ends of the conical surface 15 $7b$ and extending outwardly from the bottom of the edge-raising portion $7'$. The flat surface $7c$ also preferably extends to the point 7 . Suitable means is employed for supplying heat to the tool 5 and in the embodiment shown, the head 20 6 is provided with a shank $6'$ which screws into a handle 8 . The handle 8 has a suitable socket $8'$ and contains an electric heating element of conventional form.

In using the tool 5, the pointed insertion-portion 7 is as above indicated, inserted in the slit, the flat portion $7c$ being passed along between the edges $3'-3b$ of the stitch 3 and over the protecting fabric 2 and forming a guide for the semiconic opening surface $7'$. This portion $7'$ lifts 25 and opens the marginal edges of the slit and these edges upon reaching the bevelled edge $7b$ of the wall $7a$ are turned outwardly and downwardly beneath the outer wing portions $7d$ which merges with the flat portion $7c$. The heating of the 30 heating element thereupon supplies the necessary heat and pressing or ironing means to initially retain said folded portion in folded condition.

After initially folding down the marginal edges as above described, I apply on the reverse side 40 of the fabric beneath the folded edges of the slit a conventional fastening material such as rubber, which is sprayed beneath said initially folded marginal edges by the use of conventional spraying apparatus.

The embroidered fabric is then, preferably in one operation or simultaneously, subjected to heat and pressure which not only securely fastens 45 down the said marginal edges but also serves to discharge the protective dischargeable fabric, which, after such pressing and heating may be brushed away to leave the open faggoting channel with the cross-threads only of faggoting stitches exposed at the front side as shown in Fig. 1, while the parallel chain and connecting 50 stitch portions $3', 3b$ are concealed on the reverse side by the fastened down marginal edges 55 of the slit.

As many changes could be made in the above construction and many apparently widely different embodiments of this invention could be made without departing from the scope thereof; it is intended that all matter contained in the above description or shown in the accompanying drawing shall be interpreted as illustrative and not in a limiting sense. 5

Having described my invention, I claim:—

1. A device for folding and initially pressing 10 marginal edges of slits in fabrics, embodying, in combination, a body having adjacent to its forward end a neck portion of a predetermined width and provided with a pointed head portion extending forwardly from said neck and having an 15 edge raising surface, said body being provided at the rear of said edge-raising surface with a pressing surface extending outwardly to opposite sides of said neck portion to provide flat pressing wing portions, said body also having an 20 edge-guiding surface between said edge-raising and pressing wing portions, and means for heating said body.

2. A device for folding and initially pressing 25 marginal edges of slits in fabrics, embodying, in combination, a body having adjacent to its forward end a neck portion of a predetermined width and provided with a pointed head portion extending forwardly from said neck and having an 30 edge raising surface, said body being provided at the rear of said edge-raising surface with a pressing surface extending outwardly to opposite sides of said neck portion to provide flat pressing wing portions, said body also having an 35 edge-guiding surface between said edge-raising and pressing wing portions, said pointed head portion having beneath said edge raising surface a flattened surface continuous with the flat wing portions, and means for heating said body.

3. A device for folding and initially pressing 40 marginal edges of slits in fabrics, embodying, in combination, a body having a flat base-portion provided adjacent to its forward end with a neck portion of predetermined width, and a head portion extending forwardly from said neck portion 45 and having a conical edge-raising surface, said body being provided at the rear of said edge-raising surface with an edge-pressing surface extending outwardly to opposite sides of said neck portion to provide flat wing portions, said body 50 also being provided at the rear of said edge-raising surface with a conical edge-turning surface extending upwardly and forwardly from said neck portion, and means for heating said body.

JACK SNARCK. 55
